(57) **CLAIM**

The ornamental design for an air conditioner as shown and described.

DESCRIPTION

2.1 is a perspective view of an air conditioner showing our new design;

2.2 is an alternative perspective view thereof;

2.3 is a front elevation view thereof;

2.4 is a rear elevation view thereof;

2.5 is a left elevation view thereof;

2.6 is a right elevation view thereof;

2.7 is a top plan view thereof; and

2.8 is a bottom plan view thereof.

The broken lines shown in the drawings depict portions of the air conditioner that form no part of the claimed design; the shade lines represent surface shading and are not surface ornamentation or decoration.
